UNITED STATES PATENT OFFICE

FÉLIX FRÉDÉRIC RUAU, OF DEPTFORD, LONDON, ENGLAND

CIGARETTE-MAKING MACHINERY

Application filed July 23, 1928, Serial No. 294,753, and in Great Britain August 20, 1927.

The present invention is for improvements in or relating to cigarette making machinery, and more particularly to a device for applying adhesive to a travelling web of cigarette paper fed through a cigarette making machine of the continuous rod type, and has for its object the provision of a device in which the receptacle for the adhesive may be removed and a duplicate substituted therefor without necessitating any delicate adjustments to any part of the device.

There has hitherto been used upon cigarette making machines of the continuous rod type a device wherein a receptacle adapted to receive adhesive is mounted upon a cigarette making machine in such a manner that a plunger movable in the receptacle is adapted to force adhesive through a nozzle formed in one end of the receptacle on to the surface of a furnishing roller from which the adhesive is taken by a rotary wheel which applies the same to a travelling web of cigarette paper.

With a device of the above character, however, it is essential that the mouth of the nozzle in the adhesive receptacle and the surface of the furnishing roller shall fit very accurately together so as to ensure that the adhesive is fed correctly from the receptacle to the surface of the furnishing roller.

This requires very accurate fitting and also necessitates fine adjustments being made every time the receptacle is removed for re-filling.

The present invention consists of a device for applying adhesive to a travelling web of cigarette paper which comprises in combination a receptacle adapted to accommodate adhesive (for example starch), a plunger operable to force the adhesive through an outlet opening formed in the said receptacle, a nozzle formed in a concave surface arranged to engage with the surface of a furnishing roller so as to supply a film of adhesive to said roller and a readily detachable connection adapted to establish a communication between the nozzle and the outlet opening of the receptacle.

The invention is more particularly de-

scribed with reference to the accompanying drawings in which:—

Fig. 1 is a side elevation partly in section of the apparatus.

Fig. 2 is a detailed view in the direction of arrow "A", Fig. 1.

Referring to the drawings, a receptacle 1 adapted to contain starch paste or like adhesive is carried upon a standard 2 mounted upon the frame of the cigarette making machine.

The receptacle 1 is adapted to be detachably secured by means of a bayonet joint 3 to a member 4 which is bolted to the standard 2. A plunger 5 carried by a screw threaded rod 6 is continuously moved downwardly in said receptacle whilst the machine is in operation so as to force the paste out through an outlet opening 7 formed in the lower end of the receptacle 1 and to which a flexible tube 7^a is adapted to be connected. The plunger is operated in the following manner:—

A spindle 8 mounted in a gear box 9 is rotated by a pulley 10 driven from the main drive of the machine. The spindle 8 carries a worm 11 which meshes with worm wheel 12 carried on a cross spindle 13. Another worm (not shown) is mounted on the spindle 13 and this meshes with a worm wheel 14 which is bolted to a flanged sleeve 15. The sleeve 15 is adapted to rotate on a cylindrical extension 16 of the member 4 and the upper portion of the sleeve 15 constitutes one half of a dog clutch 17. A screw threaded hole is formed in the middle of the member 4 and forms a nut for the screwed rod 6 which carries the piston. The second element of the dog clutch 17 is formed on a collar 18 which is adapted to slide over the threaded rod 6, but is prevented from rotating relatively thereto by means of a key working in a spline 19.

The outlet opening 7 of the receptacle 1 is connected by a piece of detachable flexible tubing 7^a to a nozzle 20 formed with a concave surface 20^a arranged to engage with the periphery of a furnishing roller 21 having a concave groove formed in the periphery thereof. The surface in which the nozzle is

formed is maintained in an accurate position relatively to the furnishing roller so that the supply of adhesive to the said roller is constant and the position of the nozzle need not be varied or altered once the machine is set.

5 A paste applying wheel 22 is adapted to engage with the periphery of the furnishing roller and transfer paste to the edge of a travelling web of cigarette paper 23.

10 When the machine is operating the plunger 5 forces the adhesive through the tube 7^a and the nozzle 20 in a regular stream so as to supply a film of adhesive to the furnishing roller 21. As soon as the piston has reached the bottom of the receptacle 1 the operator lifts the collar 18 on the rod 6 and clamps the same, thus breaking the dog clutch connection so that the rod 6 ceases to rotate and the piston remains stationary. The operator 15 then disconnects the union 24 and rotates the rod 6 by means of the hand wheel 25 until the piston 5 is at the top of its stroke whereupon a full pot of paste is substituted.

20 It will be seen therefore that very little time is lost in changing the paste receptacle as it is not necessary to disturb the accurately set nozzle and furnishing roller.

25 If desired, a shearing pin or a similar device may be fitted to the driving pulley 10 so that in the case of any obstruction occurring, the pin breaks and no damage is done to the mechanism.

30 What I claim as my invention and desire to secure by Letters Patent is:—

35 In a device for applying adhesive, the combination with a receptacle having an aperture at one end thereof through which adhesive may be introduced and discharged, a piston movable in said receptacle toward the 40 apertured end thereof for discharging adhesive from the latter, a threaded piston rod associated with said piston, a frame on which said receptacle is removably supported, threaded means held against rotation by said 45 frame and engaging the threaded portion of said piston rod, a rotatable element journaled on said threaded means, a member splined to said piston rod and having a disengageable clutch connection with said rotatable element, an adhesive furnishing roller, a nozzle disposed adjacent the periphery of said roller for delivering adhesive thereto, and a detachable flexible conduit interposed between 50 said aperture and said nozzle for conveying adhesive to the latter whereby said receptacle may be readily removed for filling and replaced without disturbing the relative positions of said nozzle and roller.

55 In testimony whereof I hereunto affix my signature.

FÉLIX FRÉDÉRIC RUAU.
